SPLIT DRUM WINDING MACHINE

Augustin Laché, Guebwiller, France, assignor to
 Société Anonyme Nouvelle Société de Con-
 struction late N. Schlumberger & Cie., Gueb-
 willer, France

Application January 25, 1934, Serial No. 708,326
 In France February 6, 1933

2 Claims. (Cl. 242—43)

The object of the present invention is a split drum winding frame device in which, in order to avoid variable tensioning of the thread, said thread only goes through the drum according to a secant subtending an arc of small amplitude, the points of entrance and of exit of the thread being thus positioned in close proximity and the thread being held in the drum by a strip positioned within said drum and under which said thread passes.

The winding device which forms the subject matter of the invention possesses the following features:

1.—The strip positioned within the drum is split obliquely in its center, the front edge of the slit presents a raised beak which determines the automatic engagement of the thread under the strip and the rear edge is also slightly raised in order to allow the automatic exit of the thread when the bobbin moves out of contact with the drum.

2.—In its middle portion the drum is provided with a thread catching slot similar to that which exists on the split drum winding machines of the types known at present, said slot acting in combination with the strip, as defined in 1, to obtain automatic and instantaneous engagement of the thread under the strip.

On the attached drawings:

30 Figure 1 is a diagram, in section, of a split drum winding device constructed according to the invention;

35 Figures 2 and 3 show, in elevation and in perspective, the manner according to which the strip positioned within the drum is constituted;

Figure 4 is a front view of a split drum built according to the invention;

40 Figures 5, 6, 7 and 8 show how, with the application of this strip, the thread is caught by said strip and then ejected by it.

In the split drum winding machines the arrangement of which is known, the thread which is to be wound passes through the drum almost according to a diameter of said drum.

45 In passing through the drum in this manner the thread is subjected to a tension the magnitude of which varies according to the position of the winding-on point on the bobbin. On the points of the slot, that is to say when the winding on of the thread is on the edges of the bobbin, the tension to which said thread is subjected is very much greater than when it is engaged in proximity to the middle of the slot.

50 In order to overcome this difficulty, winding machines in which the thread passes through the

drum only according to a secant subtending an arc of small amplitude have already been imagined, the points of entrance and exit of the thread thus being in close proximity on the outer surface of the drum.

This arrangement necessitates a special organ which prevents the thread from coming out of the slot; this special organ is constituted by an inside strip underneath which the thread is constantly engaged.

This device gives excellent results but it has the disadvantage of necessitating a comparatively long time for threading the thread into the slot and under the strip; indeed, as said strip is constituted by a single cross piece which only permits of the engagement of the thread by one of its extremities, it will readily be seen that, in order that it may be possible to pass the thread underneath the strip, it will be necessary to provide one or more leads to the slot, said leads terminating at the edges of the drum in openings in which the thread is held by hand while the drum is rotated in order to obtain the passage of the thread underneath the strip.

The device which forms the subject matter of the present invention presents all the advantages of the split drums of the types above indicated but makes it possible to eliminate the disadvantages by making threading absolutely automatic as in the case of ordinary split drum winding machines.

As will be seen on the drawings, in a split drum winding machine constructed according to the invention, strip 1 positioned within the drum is held in proper position by a counterweight 2. The strip proper is provided, at its center, with an oblique slot 3 and, on the edge of said slot, on the side towards which the engagement of the thread occurs is a raised beak 4 terminated by a hook 4' under which the thread slips at the moment when it drags in the thread catching slot of the drum so that when the thread is pushed laterally by oblique slot 7 of said drum it is compelled to follow slot 3 and to locate itself underneath the strip.

The rear edge of slot 3, on the side opposite to that which bears beak 4', is slightly raised at point 6', this beak like conformation is however less pronounced than in the case of beak 4.

The drum is set up in the usual manner, that is to say that it comprises an oblique slot 7 as well as a longitudinal thread catching slot 5 provided along the medial plane of the drum perpendicular to the axis of rotation of said drum.

In order to pass the thread under the strip

when starting up the winding machine or after mending a break, it is sufficient to place the bobbin which is in course of filling into contact with the drum to cause it to rotate; the engagement 5 of the thread in the drum takes place automatically and in the following manner:

When bobbin 8 which is to be filled is applied onto the drum the thread drops into thread catching slot 5 (position shown in Figure 5); it 10 comes into engagement beneath hook 4' then, following slot 3, it positions itself under the strip as soon as oblique slot 7 of the drum pushes it laterally (position shown in Figure 6). As soon as in following slot 3 the thread has escaped 15 through exit 6 of the slot, it remains held underneath strip 1 when being wound by sliding under beak 6'.

It will be seen that this operation of engagement of the thread occurs owing to the device 20 which forms the subject matter of the invention in an entirely automatic manner and without necessitating any special operation.

Beak 6' is raised only just to the extent necessary to maintain the thread underneath the strip 25 in this position at the moment of winding so that when the bobbin is raised (position shown in Figure 7) the thread forms an angle with the plane of the strip and, sliding on the inner surface of beak 6', it tends to engage above said beak 30 and this occurs as soon as, owing to the rotation of the drum, oblique slot 7 of said drum exerts a lateral pressure on said thread; the thread is then driven out of the drum (position shown in Figure 8).

35 It will be appreciated that this arrangement

is particularly advantageous in the case of assembling threads when, on account of the breakage of one of the ends, the bobbin is automatically raised for, in this case, owing to the device described, the broken thread, or threads, which are not broken are released and do not continue to follow the to and fro movement of the drum.

5 It is to be understood that the shapes given to beaks 4 and 6' and to hook 4' may be varied slightly according to the dimensions of the drum and also according to the position of the winding bobbin on said drum and that the invention may be embodied in other forms within the scope of 10 the following claims.

15 What I claim is:

1. A winding machine of the type described comprising, in combination, a drum, a thread catching slot on said drum, an oblique slot on 20 said drum and a strip positioned within said drum, said strip being slotted obliquely along its center.

2. A winding machine of the type described comprising, in combination, a drum comprising at its medial portion a thread catching slot, a second slot on the same said drum extending 25 obliquely along the whole length of said drum and a strip positioned within said drum, said strip being obliquely slotted along its center, the front edge of said slot of said strip being provided with means co-operating with said thread catching 30 slot of said drum for the purpose of causing the automatic and instantaneous engagement of the thread underneath said strip.

AUGUSTIN LACHÉ. 35
